UNITED STATES PATENT OFFICE.

COLUMBUS A. THOMAS, OF FAYETTEVILLE, NORTH CAROLINA.

GAS-REGULATING VALVE.

1,140,420.

Specification of Letters Patent. Patented May 25, 1915.

Application filed May 16, 1914. Serial No. 839,100.

To all whom it may concern:

Be it known that I, COLUMBUS A. THOMAS, a citizen of the United States, residing at Fayetteville, in the county of Cumberland and State of North Carolina, have invented 5 certain new and useful Improvements in Gas-Regulating Valves, of which the following is a specification, reference being had to the accompanying drawings.

10 This invention relates to certain improvements in gas regulating valves and has relation more particularly to a pilot light; and the object of the invention is to provide a device of this general character wherein the 15 possibility of clogging or fouling the pilot, particularly by corrosion, is substantially entirely obviated.

The invention consists in the details of construction and in the combination and arrangement of the several parts of my improved device whereby certain important advantages are attained and the device is rendered simpler, less expensive and otherwise more convenient and advantageous for 25 use, all as will be hereinafter more fully set forth.

The novel features of the invention will be carefully defined in the appended claim.

In order that my invention may be the 30 better understood, I will now proceed to describe the same with reference to the accompanying drawings, wherein—

Figure 1 is an elevational view of a pilot constructed in accordance with an embodiment of my invention, a main burner being shown in fragment and a supply pipe being indicated in section; and Fig. 2 is a longitudinal sectional view taken through the cylinder included in my improved pilot, as 40 herein disclosed, the coacting portions of the pipes or tubes being shown in elevation and in fragment.

As disclosed in the accompanying drawings, 1 denotes a cylinder of predetermined 45 dimensions and having its opposite ends open, such open ends being adapted to be closed by the heads 2 and 3 removably engaged therewith, such engagement being herein disclosed through the medium of conventional threads. The cylinder 1 is adapted 50 to contain a compressible body 4 preferably of mineral wool, although I have found in practice that such body will operate with advantage when formed of cotton or felt.

55 As herein disclosed, the body 4 is interposed between the reticulated members 5,

preferably formed of wire mesh, and one of such members is adapted to be engaged by the inner extremity of the controlling screw 6, herein disclosed as threaded through the 60 head 2 whereby it will be observed that the density of such body 4 may be regulated in order to control the flow of the gaseous fluid through such cylinder.

In order that the body 4 may operate with 65 greater facility, especially when the flow through the pilot is adapted to be increased, I find it of advantage to embed within such body 4 the expansible member 17, herein disclosed as a coil spring possessing the 70 requisite tension. In communication with the cylinder 1 in close proximity to the head 2 is a tube or pipe 7 adapted to lead from the supply pipe 8 of the main gas burner, as is generally done in devices of this character. 75 The head 3 is provided with a nipple 9 having its exterior surface threaded and adapted to be engaged by the sleeve 10 slidably mounted upon the tube or pipe 11, which pipe or tube 11 is adapted to be properly 80 directed so as to terminate in close proximity to the main burner 12, such extremity being provided with the tip 14 of any ordinary or preferred type. The extremity of the tube or pipe 11 coacting with the nipple 9 is 85 provided with an enlargement or annular flange 15 adapted to register with the free end of the nipple and for the purpose of effecting a proper joint, I find it of advantage to interpose between such head or flange 15 and the nipple 9 a washer 16 formed of asbestos or the like. It is thought to be obvious that the sleeve 10 serves to effect and maintain the desired joint between such pipe or tube 11 and the nipple 9. It is to be observed that the body 4 is interposed between 90 the head 3 and the delivery end of the induction pipe 7 whereby the chamber 1^a is afforded to hold the gas before it passes through the body 4.

100 In view of the foregoing, it will be readily perceived that the controlling or regulating screw 6 does not coat with or engage a metallic seat for the control of the gaseous fluid through the pilot, and it is this arrangement which serves to avoid the manifest disadvantage in the pilots generally employed, as such engagement or coaction with the controlling screw has been found to result in such corrosion as to materially interfere 105 with the operation of the pilot and in some instances to such an extent as to so clog or

foul the conducting passage-ways or tubes as to entirely close the same.

From the foregoing description, it is thought to be obvious that a gas regulating valve constructed in accordance with my invention is of an extremely simple and comparatively inexpensive nature and is particularly well adapted for use by reason of the convenience and facility with which it 5 may be assembled and by reason of the effectiveness with which it performs its functions, and it will also be obvious that my invention is susceptible of some change and modification without material departure 10 from the principles and spirit thereof and for this reason I do not wish to be understood as limiting myself to the precise arrangement and formation of the several parts herein 15 shown in carrying out my invention in practice.

I claim:

A valve of the character described comprising a tubular member closed at opposite

ends, a screw threaded through one end of the member, the opposite end being provided 25 with a discharge opening, said member being provided in a side thereof with an induction opening, a permeable and compressible body positioned within the tubular member and interposed between the end provided with the discharge opening and the induction opening, the space between the inner end of the compressible body and the end of the tubular member affording an expansion chamber, an expansible member embedded within the compressible body, and a perforated member disposed in contact with the inner end of the compressible body and with which the inner end of the screw is 30 adapted to contact.

In testimony whereof I hereunto affix my signature in the presence of two witnesses.

COLUMBUS A. THOMAS.
